(57) **CLAIM**

The ornamental design for a infant event monitoring bracelet, as shown and described.

DESCRIPTION

FIG. 1 is a perspective view of the infant event monitoring bracelet of the present invention showing my new design with the phantom lines depicting solely environmental structure and forming no part of the claimed design;

FIG. 2 is a left side elevational view thereof;

FIG. 3 is a right side elevational view thereof;

FIG. 4 is a top plan view thereof;

FIG. 5 is an end view thereof; and,

FIG. 6 is a bottom plan view thereof.
